UNITED STATES PATENT OFFICE.

JOHN M. MCINTYRE, OF LOCKPORT, NEW YORK.

METHOD OF AND APPARATUS FOR SEPARATING DUST FROM AIR.

SPECIFICATION forming part of Letters Patent No. 294,248, dated February 26, 1884.

Application filed July 5, 1883. (No model.)

To all whom it may concern:

Be it known that I, JOHN M. MCINTYRE, of Lockport, in the county of Niagara and State of New York, have invented a new and useful

5 Improvement in Method of and Apparatus for Separating Dust from Air, of which the following is a specification.

This invention relates to an improvement in that class of dust-collectors which are employed 10 in mills for freeing the dust-laden air discharged from middlings-purifiers and similar machines from the dust or solid particles which it contains. In dust-collectors as ordinarily 15 constructed the dust-laden air is sifted or strained through a cloth, which intercepts the dust and permits the air to pass through. These filter-cloths are an obstruction in the air-passage, whereby the air-current is retarded, necessitating a proportionate greater speed 20 of the fan in order to effect the desired separation on the purifier-sieve. The resistance which the filter-cloth opposes to the air-current increases as the meshes of the cloth become filled with dust, and decreases as the 25 meshes are cleared by the jarring devices or brushes with which dust-collectors are usually provided, so that this resistance is variable, causing corresponding variations in the force 30 of the air-current and an unequal purification.

The object of my invention is to overcome 35 these difficulties by separating the dust from the air without the use of filter-cloths; and my invention consists in the method and apparatus whereby the dust is separated from the air by centrifugal force acting upon the dust particles in such manner as to drive them out of the air-current into a collecting-chamber, while the air is permitted to move on, as will be hereinafter fully set forth, and pointed out in the 40 claims.

In the accompanying drawings, consisting 45 of three sheets, Figure 1 is an end elevation, and Fig. 2 a side elevation, of my improved dust-collector. Fig. 3 is a longitudinal sectional elevation of the machine. Fig. 4 is a cross-section in line $x-x$, Fig. 3. Fig. 5 is a cross-section on an enlarged scale of a portion of the dust-collecting case. Fig. 6 is a longitudinal section of the trapped dust-discharge. 50 Fig. 7 is a cross-section in line $x-x$, Fig. 6.

Figs. 8 and 9 are cross-sections in line $y-y$, Fig. 6, showing the different positions of the valve.

Like letters of reference refer to like parts in the several figures.

A represents the centrifugal dust-separator, 55 and a the spout or conduit through which the dust-laden air is conducted from the middlings-purifier or other machine to the separator.

b represents the horizontal shaft of the separator turning in bearings b' , and provided 60 with a driving-pulley, B.

C represents the wings or beaters of the separator fastened to the outer side of a dished head or disk, D, which is secured to the shaft b .

E represents a chamber, arranged opposite 65 the receiving ends c of the beaters C, and communicating with the spout a , so as to conduct the dust-laden air between the inner or receiving ends c of the beaters. The latter extend outwardly and forwardly on the outer side of 70 the head D, and are provided with a curved shield or hood, F, which incloses the spaces between the beaters from their receiving ends c to a point near the outer horizontal edges of the beaters, whereby the air which is drawn 75 between the beaters is compelled to move onward in the direction of the arrows in Fig. 3 and prevented from being blown backward into the chamber E.

G represents the dust-collecting chamber 80 which surrounds the revolving beaters C. The inner wall of this chamber is formed by a perforated cylindrical shell, g , arranged in close proximity to the outer edges of the beaters. The upper portion of the outer wall of 85 the chamber G is made concentric with the perforated shell g , and its lower part has the form of a hopper, as shown at g' , and is provided at its bottom with a conveyer-trough, H, and a screw-conveyer, h , whereby the dust 90 falling into the hopper is removed. The perforations in the shell g are preferably made in the form of horizontal slots i , having their rear edges projecting inwardly beyond the inner surface of the shell g , as shown in Fig. 5, 95 to facilitate the entrance of the dust into the openings. The trough H is provided with a trapped discharge, whereby the dust is delivered from the chamber G without permitting the air to escape with it. This trapped 100

discharge is preferably constructed in the following manner:

- j* represents the partition arranged in the conveyer-trough *H*, near its discharge end; and
 5 *k* is an opening formed in the lower portion of the partition for the discharge of the material from the trough proper into the space between the partition *j* and the end wall, *j'*, of the conveyer-trough.
- 10 *L* represents a rotating hollow cylindrical valve secured to the shaft *h'* of the conveyer *h*, between the partitions *j* and *j'*. The inner wall of the valve *L* is provided with an opening, *l*, on one side of the shaft *h'*, which is adapted to register with the opening *k* in the partition *j* once in every revolution of the valve. The periphery of the valve *L* is constructed with an opening, *m*, which is adapted to register with an opening, *n*, formed in the bottom of the space 20 between the partitions *j* and *j'*. The opening *m* is arranged diametrically opposite the opening *l*, or so that the coincidence between the openings *m* and *n* is broken when the openings *k* and *l* register, and vice versa, so that the opening *n* is closed by the cylindrical wall of the valve *L* when the conveyer discharges the material through the openings *k* and *l* into the cavity of the valve. The material so delivered into the valve is permitted to escape from 30 the same through the openings *m* and *n*, when the opening *k* is closed by the inner head of the valve *L*, and by this means the escape of air through the dust-discharge is prevented and air-currents in the chamber *G* are avoided.
- 35 *O* and *O'* represent the end walls of the chamber *G*. The wall *O* is provided with an opening, *O'*, through which the dust-laden air enters from the chamber *E* into the space between the receiving ends of the beaters *C*.
- 40 The hood *F* fits snugly in this opening to prevent, as far as practicable, the air from passing along the outer side of the hood. The wall *O'* is provided with an opening, *O''*, through which the air which has been freed from dust escapes from the separator *A*.
- 45 *P* represents a suction-fan mounted on the shaft *b*, and arranged in a casing, *p*, contiguous to the wall *O'*, the opening *O''* in said wall forming the eye of the fan-case *p*. The fan *P* 50 draws the air from the separator *A* and discharges the same through its blast-spout *q*. If the air escaping from the spout *q* contains traces of dust, it may be discharged into an ordinary dust-room of sufficient size to permit the dust to settle, while the air escapes freely.
- 55 *r* represents an endless belt running around pulleys *r'*, *r''*, mounted, respectively, on the shafts *b* and *h'*, whereby the conveyer *h* is rotated from the shaft *b*.
- 60 If desired, the fan *P* may be mounted on a separate shaft and driven with greater or less speed than the separator *A*.
- 65 The dust-laden air enters from the chamber *E* between the receiving ends of the beaters *C*, and is driven by the latter outwardly and

forwardly in the direction of the arrows in Fig. 3. The centrifugal action of the beaters *C* drives the dust against the surrounding perforated casing *g*. The air is prevented from entering said casing, as the latter is not provided with any outlet for air; but the dust, owing to its greater specific gravity, is driven through the perforations of the casing *g* into the chamber *G*, and drops in the latter upon the hopper-shaped bottom, and thence into the conveyer-trough *H*, from which it is removed by the intermittent action of the discharge device. The projecting rear edges of the slots *i* in the casing *g* greatly facilitate the entrance of the dust into the chamber *G*, as they intercept the dense layer of dust which is driven by the beaters *C* along the inner surface of the casing *g* in the direction of the arrow in Fig. 5. The dust is in this manner 85 separated from the air by the centrifugal action of the beaters, which drive the dust out of the air-current which moves through the separator *A*, between the head *D* and hood *F*, while the air which has been freed from dust 90 is permitted to move on toward the fan *P*.

The separator *A* accelerates the movement of the air through the machine, instead of retarding it like ordinary dust-collectors, which operate by filtering or straining the air through 95 cloths, and as the operation of the separator *A* is uniform at all times, it insures the uniform and regular operation of the purifying-machines with which it is connected. When the centrifugal separator is sufficient to create 100 the desired air-current, the auxiliary fan may be omitted.

I claim as my invention—

1. The herein-described method of separating dust from air, which consists in driving 105 the dust particles out of the air-current by centrifugal force into a closed receiving-chamber, while the air which has been freed from dust is permitted to escape in a different direction, substantially as set forth.

2. In a machine for separating dust from air, the combination of revolving beaters, and a closed receiving-chamber having an inner perforated wall surrounding said beaters, and inlet and outlet openings through which the dust-laden air is conducted to the beaters, and the purified air is permitted to escape therefrom, substantially as set forth.

3. In a machine for separating dust from air, the combination of revolving beaters, and a 120 closed receiving-chamber having an inner perforated wall surrounding said beaters, and inlet and outlet openings through which the dust-laden air is conducted to the beaters, and the purified air is permitted to escape therefrom, 125 and a trapped discharge device, whereby the dust is removed from the closed chamber without permitting the air to escape therefrom, substantially as set forth.

4. In a machine for separating dust from air, 130 the combination of revolving beaters, and a closed receiving-chamber having an inner per-

forated wall surrounding said beaters, and inlet and outlet openings through which the dust-laden air is conducted to the beaters, and the purified air is permitted to escape therefrom, and an auxiliary fan, whereby the air is caused to flow through the separator, substantially as set forth.

5. In a machine for separating dust from air, the combination of revolving beaters with a closed receiving-chamber having its inner wall constructed with openings having inwardly projecting rear edges, substantially as set forth.

6. The combination, with the chamber G, having an inner perforated wall, g, of revolving beaters C, a head, D, to which the beaters are secured, and a hood, F, by which the spaces between the receiving portions of the beaters are closed, substantially as set forth. 15
